(57) **CLAIM**

The ornamental design for a combination flashlight and camera, as shown and described.

DESCRIPTION

FIG. 1 is a front perspective view of a combination flashlight and camera;

FIG. 2 is a front view of the combination flashlight and camera in FIG. 1;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a front perspective view of another embodiment of a combination flashlight and camera;

FIG. 9 is a front view of the combination flashlight and camera in FIG. 8;

FIG. 10 is a rear view thereof;

FIG. 11 is a left view thereof;

FIG. 12 is a right view thereof;

FIG. 13 is a top view thereof; and,

FIG. 14 is a bottom view thereof.

The broken lines show portions of the combination flashlight and camera which are not claimed.

1 Claim, 12 Drawing Sheets
